LEDGER HOLDER

John R. Huber, Ravenna, and Homer J. Wise,
Kent, Ohio

Application September 24, 1948, Serial No. 148,742

Term of patent 3½ years

(Cl. D74—2)

To all whom it may concern:

Be it known that we, John R. Huber and Homer J. Wise, citizens of the United States and residents respectively of Ravenna, Portage County, Ohio, and Kent, Portage County, Ohio, have invented a new, original, and ornamental Design for a Ledger Holder, of which the following is a specification, reference being had to the accompanying drawing, forming a part thereof.

In the drawings, Fig. 1 is a perspective view of a ledger holder showing our new design, and Fig. 2 is a side elevational view of the same.

We claim:

The ornamental design for a ledger holder, as shown.

JOHN R. HUBER.
HOMER J. WISE.
